PLAYGROUND SLIDE WITH CIRCULAR STAIRCASE

Robert S. Wormser and Ronald L. Ewers, Hillsdale,
Mich., assignors to Game Time, Inc., Litchfield, Mich.

Filed Dec. 20, 1971, Ser. No. 210,300

Term of patent 14 years

Int. Cl. D21—03

U.S. Cl. D34—5 E

FIG. 1

FIG. 2

FIG. 3

FIG. 4

FIG. 5

FIG. 1 is a perspective view taken from the front and left side of a playground slide with circular staircase in accord with our new design,

FIG. 2 is a perspective view as taken from the rear and right side of the design,

FIG. 3 is a front elevational view of our new design,

FIG. 4 is a rear elevational view, and

FIG. 5 is a top plan view of our playground slide with circular staircase.

We claim:

The ornamental design for a playground slide with circular staircase, substantially as shown and described.
